US00D886202S

(12) **United States Design Patent** (10) **Patent No.:** **US D886,202 S**
(45) **Date of Patent:** **** Jun. 2, 2020**

(54) **MANCALA GAME SET**

(71) Applicant: **Carolyn Hsu**, San Francisco, CA (US)

(72) Inventor: **Carolyn Hsu**, San Francisco, CA (US)

(**) Term: **15 Years**

(21) Appl. No.: **29/629,804**

(22) Filed: **Dec. 15, 2017**

(51) **LOC (12) Cl.** **21-01**

(52) **U.S. Cl.**

USPC **D21/342**; D21/335; D21/366

(58) **Field of Classification Search**

(57) **CLAIM**

The ornamental design for a mancala game set, as shown and described.

DESCRIPTION

FIG. 1 is a top plan view of a mancala game set, shown in an open condition;

FIG. 2 is a front, top surface perspective view thereof;

FIG. 3 is a bottom view thereof;

FIG. 4 is a front, bottom surface perspective of the mancala game set shown in a closed condition, the rear, bottom perspective view being a mirror image;

FIG. 5 is a right side, bottom surface perspective view thereof; and,

FIG. 6 is a left side, bottom surface perspective view thereof.

1 Claim, 6 Drawing Sheets
